Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;

FIG. 2 is a bottom view thereof;

FIG. 3 is a rear perspective view thereof; and,

FIG. 4 is a cross section taken through line 4-4 of FIG. 2. The broken lines immediately adjacent to the shaded areas define the bounds of the claimed design and form no part thereof. The solid line that is not immediately adjacent to the shaded areas is claimed. The unshaded region between the shaded areas forms no part of the claimed design. The broken lines depicting the remainder of the shoe show features that form no part of the claimed design.
